TILT COMPENSATOR FOR TYPEWRITERS

Herman G. Hartman, Rockville, Md., assignor to
Underwood Corporation, New York, N. Y., a
corporation of Delaware

Application December 12, 1947, Serial No. 791,290

3 Claims. (Cl. 197—82)

1

This application relates to an improvement in paper carriages for typewriters and is particularly directed to a counterbalancing means for such carriages. Such counterbalancing is highly desirable when the typewriter is subjected to variable degrees of tilting as on board a ship or other unsteady object.

When a conventional typewriter is being used on a ship, it can not be continuously operated for when, due to the roll or pitch of the ship, the machine is tilted up on the left hand side, the component of the carriage weight which is directed along the line of motion of the carriage will, at some angle, equal the force of the carriage feeding spring and there will be no carriage escapement in response to operation of a type key. This will result in letters being typed one on top of the other and an illegible result. With a slightly greater tilt, such component of the carriage weight will be so large as to overcome the tension of the carriage feeding spring and the carriage will be involuntarily returned to the right. When the tilt is in the opposite direction, this component of the carriage weight will bear against the escapement dogs resulting in a jamming of the escapement or a possible skipping with double or more letter feed.

The roll of a ship is accentuated by bad weather or high speed such that use of a conventional typewriter is possible only intermittently. Such conditions, however, increase the duties of a radio operator whose messages must be recorded and who has heretofore been forced to resort to manual transcription at a rate considerably slower than normal.

It is therefore an object of the present invention to provide a typewriter in which the carriage is unaffected by any reasonably expected tilt of the typewriter frame.

It is also an object to provide a typewriter carriage compensated for lateral tilting of a typewriter.

A further object is to provide a counterbalance for a typewriter carriage, such device being effective at all positions of the carriage and for either direction of tilt of the machine frame.

It is also an object of the present invention to compensate a typewriter carriage for the effect of tilt by the provision of a simple and inexpensive means which may easily be disabled when not needed.

It is a still further object to provide such a compensating device in the form of an attachment applicable to existing conventional typewriters.

2

Other objects of the invention will be apparent from the specification and claims which follow.

In the drawings—

Figure 1 is a top view of the rear portion of a typewriter showing the improvement attached thereto,

Figure 2 is a side view of a rear portion of the machine, and

Figure 3 is a sectional side view taken along the line 3—3 of Figure 1.

Generally the invention comprises an attachment for the rear of a typewriter having a guide rail or rails for the support of a counterweight substantially equal in weight to the weight of the paper carriage. The counterweight is free to move on the guide rails and is attached to the carriage by a motion reversing drive in such manner that the weight is moved by the carriage in a direction opposite to the direction of carriage movement.

When the typewriter is tilted to an uneven position, the component of the carriage weight which is acting along the guide rails will, depending upon the direction of tilting, either augment or oppose the force of the carriage feeding spring and thus change the pressure of the carriage on the escapement mechanism. At certain degrees of tilt the combined forces are such that the escapement will not operate and the carriage will not escape in response to an operation of a type key. The counterweight will be similarly affected by the tilting of the typewriter base and the component of force tending to move the counterweight along the guide rail is substantially equal to that tending to change the effective force of the carriage feed spring. The carriage and counterweight are so connected that these two forces, one due to the carriage weight and one due to the counterweight, are opposed to each other and as the forces are substantially equal, there will be no change in the total of the forces tending to move the carriage.

More specifically, the invention is in the accompanying drawings shown as applied to a conventional typewriter of the type more completely disclosed in the U. S. Patent 1,696,906, issued January 1, 1929 to W. A. Dobson. Only so much of the typewriter is shown herein as is necessary to show the mode of attachment of the mechanism of the invention thereto. Referring to Figure 2, the typewriter base 10 has mounted thereon a paper carriage 11 carrying a platen 12. A spring drum 13 mounted in the base 10 is connected by a flexible tape 14 to the carriage 11 to normally bias the carriage to the left for letter

45

50

55

feeding. Also mounted in the base 10 is an escapement mechanism 15 of conventional type including a pinion 16. A carriage carried rack 17 mounted in swingable arms 18, only one of the arms shown herein, engages the pinion 16 of the escapement mechanism 15 to normally restrain the carriage 11 from movement. Escapement 15 is released by operation of a type action in the conventional manner to permit movement of the carriage during typing.

The mechanism of the present invention is applied to the above described conventional typewriter in the form of an attachment. The counterbalancing mechanism is easily attached and may, if desired, be removed when the typewriter is on a stable base. The particular embodiment of the invention chosen for description comprises a bracket 19 fixed to each end of the rear of the typewriter base 10, the brackets, as shown in Figure 1, extending appreciably beyond the sides of the base 10. A horizontal rail 20 is secured by bolts 21 between rearwardly offset portions 22 of brackets 19. A carrier 23 carrying four rollers 24 is freely movable on rail 20 between the brackets 19. Rollers 24 are confined between the body of carrier 23 and ears 25 bent off the carrier and are mounted on studs 26. The studs 26 pass through carrier 23 and rollers 24 and are secured in a counterweight 27, holding the carrier 23, rollers 24 and weight 27 in a unitary assembly. Counterweight 27 has a weight substantially equal to the weight of carriage 11. Secured by screws 28 to the upper ends of weight 27 are a pair of clamps comprising bent strips 29 and movable jaws 30 pulled into engagement with strips 29 by screws 31.

Vertically mounted on an upper forwardly projecting part of each of the brackets 19 is a rotatable pulley 32 aligned on one side with the clamps 29, 30 of the counterweight 27. A loop of flexible tape 33 is passed around the pulleys 32, one side of the loop being fastened to the counterweight 27 between the jaws 29, 30 thereof. The other side of the loop of tape 33 is clamped to the rear center of the typewriter carriage. The carriage clamp comprises a block 34 secured to the rear of the carriage 11 and a movable jaw 35 pivoted at its lower end in the carriage 11. The upper end of jaw 35 is moved into clamping engagement with block 34 by a thumb screw 36 passing through a hole therein and screwed into a threaded hole in carriage 11. Release of this clamp will free the carriage of load due to the inertia of the counterweight.

When the carriage 11 and counterweight 27 are connected together by the flexible tape 33, it will be seen that they travel in unison but in opposite directions. Hence, if the typewriter base is tilted to either side, the component of the carriage weight tending to move the carriage 11 toward the lower side will be opposed by a force due to the counterweight 27 tending to move the carriage to the higher side. As these two forces are substantially equal and are opposed, the only force effective to move the carriage 11 will be that due to the spring drum 13 which force is independent of the tilt of the typewriter. The carriage 11 will therefore be moved by spring drum 13 under control of the escapement mechanism 15 in the same manner when the typewriter is on a tilting base as when the base is in a normal level position.

It will be understood that many variations and changes are possible without departing from the scope of the invention disclosed herein.

What is claimed is:

1. The combination with a typewriter having a frame, a carriage slidable on said frame, a cylindrical rotary platen in said carriage, a spring on said frame to urge said carriage in a letter feeding direction and an escapement means operable to release said carriage to the urge of said spring for resulting letter space movements of said carriage, of means to render said spring and escapement means effective to letter feed said carriage in any position of said frame with respect to the force of gravity comprising a pair of pair of pulleys attached to the rear of said frame, a continuous belt around said pulleys, means for releasably attaching said belt to said carriage, a rail on said frame, a counterweight movable thereon in a direction parallel to the direction of motion of said carriage and means connecting said counterweight with said belt.
2. The combination of a typewriter having a frame, a paper carriage slidable on said frame, a carriage feed spring on said frame, a connection from said spring to said carriage, a carriage escapement means on said frame normally restraining said carriage against movement but operable to release said carriage to the urge of said carriage feed spring for single letter space increments of movement, said carriage, carriage feed spring and escapement means so constructed that upon sideways tilting of said frame, the weight of said carriage may overcome the urging of said carriage feed spring and thus prevent feeding of said carriage in response to release of said escapement and means to insure correct carriage feed under control of said escapement means, said means comprising a counterweight, means mounting said counterweight on said frame for movement in a direction parallel to the movement of said carriage, and means on said frame connecting said carriage and said counterweight for equal movement in opposite directions.
3. In a typewriting machine having a frame, a carriage movable thereon, a spring to urge said carriage in a letter feeding direction and an escapement means for said carriage to intermittently release said carriage to the action of said spring, said escapement means normally preventing movement of said carriage in a letter feeding direction and ineffective to oppose a return movement of said carriage, whereby upon tilting of said frame said carriage may return to the starting position or may fail to letter feed in response to an operation of said escapement means, a guide rail fixed to the rear of said frame and parallel to the direction of motion of said carriage, a counterweight freely movable thereon, a pulley at each upper rear corner of said frame and flexible means encircling said pulleys and connected on opposite sides to said carriage and said counterweight, at least one of said connections being manually releasable.
